[57] **CLAIM**

The ornamental design for a hook for supporting ceramic flower pots, as shown and described.

DESCRIPTION

FIG. 1 is a perspective view of a hook for supporting ceramic flower pots showing my new design;

FIG. 2 is a front view thereof;

FIG. 3 is a rear view thereof;

FIG. 4 is a top elevational view thereof;

FIG. 5 is a bottom elevational view thereof; and,

FIG. 6 is a left side elevational view thereof with the opposite side view being a mirror image.

The hook apparatus of the present invention is arranged to hold a ceramic flower pot holder in an upright position.

FIG. 1

FIG. 2

FIG. 3

FIG. 4

FIG. 5

FIG. 6
